UNITED STATES PATENT OFFICE.

JAMES C. DAWSON, OF WEBSTER GROVES, MISSOURI, ASSIGNOR TO ELMA N. DAWSON,
OF WEBSTER GROVES, MISSOURI.

LOOSE-LEAF BINDER.

Application filed December 28, 1926. Serial No. 157,466.

This invention relates to loose leaf binders, and has for its principal object to provide a novel binder assembly that can be applied to a variety of uses now imperfectly served by other structures, and which has particular advantages in connection with flexible back binders of the class now generally fitted with double headed screw devices.

Other objects and advantages of the invention will become apparent as the description is read in connection with the accompanying drawings, in which—

Fig. 1 is a perspective view of a flexible back binder made according to this invention, a portion of one leaf being broken away and the binder mechanism being unfastened and slightly displaced;

Fig. 2 is a side elevation of the metallic portion of the binder;

Fig. 3 is a plan view of the same; and

Figs. 4 and 5 are transverse sectional views on the planes indicated by the lines 4—4 and 5—5 of Fig. 3.

Referring to Figs. 1, 2, 3, 4 and 5, 10 indicates generally a flexible back equipped with tongues 11 and 12, to which a stack of leaves are to be fastened. In devices now in general use these tongues are perforated and adjustable double headed screws are inserted 30 through the tongues and the sheets to be bound.

According to this invention such screws are replaced by binder mechanism including a lower binder bar 13, an upper auxiliary floating binder bar 14, and an upper binder bar 15. The bars 13 and 14 are equipped with telescoping posts 16, the outer or tubular sections 17 of which are carried by the bar 14. The bar 13 is fixed in suitable manner to the tongue 11, 40 and the bar 15 is similarly fixed to the tongue 12.

A single locking post 18, carried by the bar 13, projects upwardly through perforations in the bars 14 and 15, and has a head 19 for operation with a keyhole slot 20 in a latch bar 21, slidably mounted on the bar 15, by the pins 22 passing through the slots 23.

In order to prevent twisting in use the bars 14 and 15 are interlocked by the simple expedient of providing one of them with notches 24, adapted to receive tongues 25 on the other.

The head 19 is preferably carried by a screw 26 (Fig. 5), threaded in the post 18, 55 whereby the length of the latter may be

varied, and hence the capacity of the binder may also be varied.

The relative positions of the parts when the binder is in use are illustrated in Figs. 4 and 5. When it is desired to remove a sheet 60 or a stack of sheets, the latch bar 21 is operated to release the head 19, when the upper binder bar 15, with its tongue and the corresponding portion of the back, may be swung to the left in Fig. 1 to a position entirely 65 clear of the remainder of the mechanism. The auxiliary binder bar 14, with a portion or all of the leaves, may then be readily removed, and after the desired changes have been made it can be replaced without any interference of 70 the bar 15 with the tongue 12.

The advantage of this structure, and other forms that will readily occur to those skilled in the art over the double headed screws now in common use, will be apparent from the 75 foregoing description and the drawings. Insofar as I am aware, this is the first binder mechanism applicable to flexible back binders that will permit sheets to be readily removed and replaced, and that can be relied 80 upon in service.

I claim as my invention—

1. In a loose leaf binder, a back, spaced tongues on the back, a lower binder bar secured to one of said tongues, posts on the lower binder bar adapted to extend through perforations in sheets to be bound, an upper binder bar secured to the other tongue, a floating auxiliary upper binder bar having posts telescoping with posts on the lower binder 90 bar, projections on the ends of the upper binder bar engaging notches in the ends of the auxiliary binder bar to hold said binder bars in alignment, and latch means carried by the upper binder bar for securing the bars 95 in binding relation to sheets on the posts.

2. A commercial article comprising a lower binder bar, an auxiliary upper binder bar, telescoping posts carried by said bars, a main upper binder bar lying along the auxiliary 100 binder bar, a locking post on the lower binder bar and projecting through the other bars, and a latch cooperating with the locking post for securing the bars together.

3. A commercial article comprising a lower binder bar, an auxiliary upper binder bar, telescoping posts carried by said bars, a main upper binder bar lying along the auxiliary binder bar, a locking post on the lower binder 105 bar and projecting through the other bars, 110

and a latch bar slidably mounted on the upper binder bar and cooperating with the locking post to secure the bars together.

4. A loose leaf binder comprising top and bottom covers, a flexible back connecting the covers, upper and lower spaced tongues between the covers, a floating binder bar located between the tongues, two pairs of symmetrically disposed telescoping binder posts carried by the lower tongue and the floating binder bar, a centrally disposed locking post rising from the lower tongue, the floating binder bar and the upper tongue having openings aligned with the locking post, a locking screw having threaded engagement with the locking post and having its upper end extending loosely thru said openings in the upper tongue and the floating binder bar, and a latch plate movably mounted on the upper tongue and having a locking engagement with the screw to prevent separation of the tongues.
5. A loose leaf binder comprising top and bottom covers, a flexible back connecting the covers, upper and lower spaced tongues between the covers, a floating binder bar located between the tongues, two pairs of symmetrically disposed telescoping binder posts carried by the lower tongue and the floating binder bar, a centrally disposed locking post rising from the lower tongue, the floating binder bar and the upper tongue having openings aligned with the locking post, a locking screw having threaded engagement with the locking post and having its upper end extending loosely thru the openings in the upper tongue and the floating binder bar, and an endwise movable latch plate mounted on the upper tongue and provided with a key-hole slot receiving the upper portion of the locking screw, said locking screw having a head

disposed above the latch plate and of greater width than that of the narrow portion of the key-hole slot.

6. A commercial article comprising a lower binder bar, an upper binder bar, a floating binder bar disposed between the upper and lower binder bars, two pairs of symmetrically disposed telescoping posts carried by the lower binder bar and the floating binder bar, an internally screw threaded post rising from the middle of the lower binder bar, the floating binder bar and the upper binder bar having aligned openings, a headed locking screw extending thru the openings in the upper and floating binder bars and engaging the threaded interior of the locking post, and an endwise moveable latch bar mounted upon the upper binder bar and having a key-hole slot receiving the shank of the locking screw.

7. A commercial article comprising a lower binder bar, an upper binder bar, a floating binder bar disposed between the upper and lower binder bars, two pairs of symmetrically disposed telescoping posts carried by the lower binder bar and the floating binder bar, an internally screw-threaded post rising from the middle of the lower binder bar, the floating binder bar and the upper binder bar having aligned openings, a headed locking screw extending thru the openings in the upper and floating binder bars and engaging the threaded interior of the locking post, and an endwise moveable latch bar mounted upon the upper binder bar and having a key-hole slot receiving the shank of the locking screw, the floating binder bar and the upper binder bar having a projection and notch engagement to maintain the bars in alinement.

In testimony whereof I affix my signature.

JAMES C. DAWSON.
